US0D1072577S

(12) **United States Design Patent** (10) **Patent No.:** **US D1,072,577 S**
(45) **Date of Patent:** **** Apr. 29, 2025**

(54) **BAG**(71) Applicant: **YETI Coolers, LLC**, Austin, TX (US)(72) Inventor: **Jeffrey Charles Munie**, Austin, TX (US)(73) Assignee: **YETI Coolers, LLC**, Austin, TX (US)(***) Term: **15 Years**(21) Appl. No.: **29/784,007**(22) Filed: **May 17, 2021****Related U.S. Application Data**

(63) Continuation of application No. 29/701,493, filed on Aug. 12, 2019, now Pat. No. Des. 919,298, which is a continuation of application No. 29/659,837, filed on Aug. 13, 2018, now Pat. No. Des. 855,994, which is a continuation of application No. 29/594,751, filed on Feb. 22, 2017, now Pat. No. Des. 825,184.

(57)

CLAIM

The ornamental design for a bag as shown and described.

DESCRIPTION

FIG. 1 is a top, front, right perspective view of a bag showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is bottom view thereof.

The even-length broken lines showing the remainder of the bag represent unclaimed subject matter and form no part of the claimed design.

1 Claim, 5 Drawing Sheets# US D1,072,577 S
